UNITED STATES PATENT OFFICE

GEORGE S. WHITMORE, OF YAKIMA, WASHINGTON

MARKING DEVICE

Application filed October 24, 1928. Serial No. 314,777.

This invention relates to an improved marking device which embodies in a single implement a plurality of marking elements which may be selectively arranged to present 5 desired marking characters in a single line for the impression of certain data on the surface being operated on.

The marker is particularly designed for use in connection with marking fruit and 10 particularly apples which are boxed at the orchard according to variety and grade and the boxes are marked to indicate the grade, the variety and the weight of the contents 15 of the box. Ordinarily the boxes have heretofore been marked by different stamps, one for grade, one for variety and one for weight, requiring three operations to properly mark the box, and as a result of the three independent operations resulting generally in a 20 very poorly marked box in which one or more of the markings are quite liable to be illegible.

The present invention is designed to present in a single marker the various stamps necessary as to different grades, different 25 varieties and different weights, so that all of the stamps may be arranged in the printing line and the boxes, when marked, will present the data in a single line and at uniform 30 impression, with the result of better marked boxes with materially less time and labor required in the marking.

A further object of the invention is the provision of a resilient cushion for directly supporting the printing elements to thereby facilitate a substantially even impression, notwithstanding the rather uneven surface of 35 the box to which the printing is to be applied.

The invention is illustrated in the accompanying drawings, in which:

Figure 1 is a view in elevation of the improved marking implement.

Figure 2 is a section on line 2-2 of Figure 1.

Figure 3 is a sectional view illustrating more particularly the provision of the resilient cushion for supporting the printing characters.

Figure 4 is a section on line 4-4 of Figure 1.

Figure 5 is a perspective view of one of the numbering disks.

Figure 6 is a sectional view, partly in elevation, illustrating the means for holding the respective printing disks in adjusted position 55 during printing operation against casual displacement.

Figure 7 is a perspective view of one of the holders for the resilient cushion and type.

Figure 8 is a broken perspective view showing the resilient cushion and type separated 60 in order to indicate their manner of assembly.

The improved marker comprises end plates 1 and 2 loosely supported upon a shaft 3, a series of partitions 4 being also loosely supported upon the shaft intermediate the end plates. The end plates and partitions are of duplicate form, their lower portions being concentric with the shaft from which 70 said plates and partitions extend in convergent form and at the end remote from the shaft 3 such end plates and partitions are connected by a rod 5 on which intermediate the end plates and adjacent partitions 75 and intermediate the partitions is arranged a series of blocks 6.

The blocks 6 have an exterior form corresponding to the outline of the partitions and end plates and extend a sufficient distance inwardly of the rod 5 to afford a handle portion by means of which the marker is manipulated. It is understood that the blocks 6 and edges of the end plates and partitions are in coincidence throughout the length of 80 the handle portion to provide a smooth handle without obstruction, and if desired a pin 7 may be used to secure the relatively inner end of each block against play relative to the adjacent end plate or partition. 85

The marking elements, indicated at 8, are loosely arranged on the shaft 3 and rotatable thereon at will. These elements are of a size to fit between the end plate and adjacent partition or between adjacent partitions, as 90 the case may be, so that they may be independently adjusted to arrange any desired data in the printing line. The marking elements each comprise a polygonal block, preferably of wood, presenting flat surfaces 9. 100

On each of the surfaces 9 is secured a holder, preferably a metallic strip 10, having relatively convergent edge walls 11, so that the holder presents in effect an undercut channel member.

- 5 The holders, which are preferably of light metal, are secured to the respective surfaces 9 of each member 8, as by screws 12, and preferably such holders will be of somewhat less length than the corresponding dimension of the surface to which they are attached. Removably secured in each holder is a resilient cushion 13, preferably of soft rubber, as sponge rubber. The cushion is of 10 a size to fit the holder, having its side walls 14 upwardly convergent so that, when moved longitudinally into the holder, the parts are locked against separation through other than a relatively endwise sliding movement.
- 15 20 The upper surface of the cushion is recessed at 15 and the marking type, preferably a rubber strip 16 having integrally formed thereon the desired characters 17, is cemented in the channel 15 of the cushion. The vertical dimension of the cushion is somewhat greater than that of the holder, so that there- 25 by the type are supported wholly free of obstruction for the printing operation.

Each block 8 is provided at one end with 30 a pin 18 slidable in a bore 19 formed in one end of the block in parallelism to the axis, a spring 20 serving to normally project the pin beyond the end of the block. Each partition is formed with openings 21 in line with 35 the pin of the adjacent block, the openings in the partitions corresponding in number to the number of printing surfaces on the block. Thus, as the block is turned to present a desired printing surface, the pin 18 thereof engages in one of the openings or recesses 21 in the adjacent partition and holds the block in the desired printing relation.

As previously stated, the end plates, partitions and members 8 are arranged loosely 40 upon the shaft 3. This shaft is headed at 22 beyond one end plate, as 2, and is provided beyond the opposite end plate with a terminal nut 23 overlying a washer 24 and between which washer and the adjacent end plate, as 1, is arranged a coil spring 25. This construction provides for the necessary freedom of movement of the various parts to 45 permit convenient adjustment of the members 8 when desired, the spring 25 serving, following adjustment, to move the end plates, partitions and members 8 into more or less intimate contact to present a substantially rigid device for use in marking.

It is frequently desirable to combine with 50 the marking of the grade, variety and amount, a number to indicate the grower, it being customary in some localities to use such numbers, for the large shippers identify the growers by number rather than by name to facilitate the clerical work necessary to

carry on the business. Under these circumstances, a plurality of numbering disks 26 may be mounted on the shaft 3 between one end plate, as 2, and the adjacent partition. These numbering disks have printing type 70 corresponding to the numbers 0 to 9, on the respective surfaces of the block, so that by adjustment of the blocks any number up to 999 may be arranged in the printing line. The type of the numbering disks are cemented directly to the faces of the disks as interchange is not necessary in this use. The holding pins described in connection with the members 8 will also be used in connection with the numbering disks, as indicated at 27 in Figure 1.

In the use of the implement, the members 8, together with the numbering disks if such are to be used, are adjusted to present the required data in alignment at the bottom of the implement, which is the printing line. The type are then inked by pressing the same onto any desired type of ink pad and the entire data required to be imprinted on the box is applied by a single impression of the implement. By reason of the resilient cushion, the printing will be maintained uniform, regular and of substantially even impression, notwithstanding the somewhat uneven surface to which the impression is applied, and as it is important that the data be clearly legible at all times, it will be seen that the resilient cushions perform a highly desirable function in insuring this legibility while at the same time preventing injury to the type characters.

Through the construction described, the various type characters may be readily removed and others substituted, giving a wide range of utility and capacity for the particular marking implement.

What is claimed to be new is:

1. A marking implement including end plates, a series of partitions intermediate the end plates, a shaft on which said end plates and partitions are loosely mounted, a series of marking members loosely mounted on said shaft between the end plate and adjacent partitions and between the respective partitions, each marking member being movable independently on the shaft, means whereby each marking member may be temporarily secured with respect to the adjacent partition, and means on the shaft beyond one end plate to hold the parts in more or less rigid connection following the movement of the member.

2. A marking member comprising a shaft, a series of division plates loosely mounted thereon, said division plates being extended in one direction beyond the shaft, blocks intermediate the division plates beyond the shaft to provide with said division plates a handle, marking members loosely mounted on the shaft between the division plates, type

carried by the marking members, and means on the marking members to cooperate with the division plates to prevent casual displacement of the marking members.

5 3. A marking member comprising a shaft, a series of division plates loosely mounted thereon, said division plates being extended in one direction beyond the shaft, blocks intermediate the division plates beyond the
10 shaft to provide with said division plates a handle, marking members loosely mounted on the shaft between the division plates, type carried by the marking members, means on the marking members to cooperate with the
15 division plates to prevent casual displacement of the marking members, and a spring exerting pressure on all the division plates and members to hold them in adjusted position against casual displacement.

20 4. A marking device comprising end plates, a series of partitions corresponding in size and shape to the end plates, a rod passing through the end plates and partitions near one end thereof, blocks loosely mounted on
25 the rod and arranged between the end plates and adjacent partitions and between each of the partitions to space the partitions on the rod and provide a handle for the implement, a shaft mounted in the end plates and
30 partitions remote from the blocks, a series of marking members rotatable on the shaft and arranged in succession between the end plates and adjacent partitions and between the partitions, and means for temporarily
35 interlocking each marking member with its adjacent partition.

5. A marking device comprising end plates, a series of partitions corresponding in size and shape to the end plates, a rod passing
40 through the end plates and partitions near one end thereof, blocks loosely mounted on the rod and arranged between the end plates and adjacent partitions and between each of the partitions to space the partitions on
45 the rod and provide a handle for the implement, a shaft mounted in the end plates and partitions remote from the blocks, a series of marking members rotatable on the shaft and arranged in succession between the end plates
50 and adjacent partitions and between the partitions, means for temporarily interlocking each marking member with its adjacent partition, the axial length of the respective blocks and of the respective and vertically aligned
55 marking members being equal, means carried by the rod to confine the partitions and blocks, and means carried by the shaft to yieldingly confine the partitions and marking members.

60 In testimony whereof I affix my signature.
GEORGE S. WHITMORE. [L. S.]
